GEORGE CARR, OF PETTUS, WEST VIRGINIA, ASSIGNOR OF ONE-HALF TO TEELA M. LEWIS, OF CHARLESTON, WEST VIRGINIA.

JOURNAL LUBRICATOR

Application filed February 6, 1929. Serial No. 337,920.

This invention relates to new and useful improvements in lubricating devices primarily adapted for application within journal boxes and the like.

5 An object of the invention contemplates the provision of a baffle arranged adjacent the journal to prevent accumulation of waste between the journal and the brass.

Another object of the invention comprehends a guard for the baffle.

An additional object of the invention embodies an adjusting element for the baffle whereby friction and clearance therebetween may be regulated.

15 More specifically stated the baffle and guard are provided with attaching means carried upon the brass for the journal.

With the above and other objects in view, the invention further consists of the following novel features and details of construction, to be hereinafter more fully described, illustrated in the accompanying drawing and pointed out in the appended claims.

In the drawing:—

25 Figure 1 is a longitudinal sectional view taken through a journal box and wedge therefor illustrating the application of the present invention upon the brass for the journal.

Figure 2 is a vertical horizontal sectional view taken on line 2—2 of Figure 1.

Figure 3 is a perspective view of the invention per se.

Referring to the drawing in detail wherein like characters of reference denote corresponding parts, the reference character 10 indicates the conventional form of axle for railway rolling stock, and which carries wheels 11 upon the ends thereof and from which have projecting centrally thereof in

40 alignment with the axles and in oppositely disposed relation thereto, journals 12 wholly disposed within journal boxes 13; all of the above is of the usual and well known construction employed in the present forms of

45 rolling stock. A wedge 14 and brass 15 are also arranged within each of the journal boxes to engage and space the journal 12 from the journal box.

The invention comprises a plate member 16 having openings 17 arranged at spaced

intervals adjacent the upper side edge thereof and which accommodate cap screws or other fastening elements, such as indicated at 18, removably connected with the sides of the brass 15.

55 Bristles 19, carried by and upwardly and obliquely disposed upon the inner sides of each of the plates 16, are preferably formed of wire and slightly concaved in conformity with the shape of the outer side wall of the 60 journal.

Baffle plates 20, having fins 21 obliquely disposed therefrom and lying flush with the outer surfaces of the plates 16 adjacent the fastened ends thereof, are also drilled or otherwise apertured to accommodate the shanks of the fastening elements 18 in the manner shown in Figure 2 of the drawing. The remaining portions of the baffle plates 20 are outwardly, downwardly and obliquely 70 disposed with relation to the remaining portions of the plates 16, substantially as illustrated in Figures 2 and 3 of the drawing. Flanges 22, formed upon the lowermost ends of the baffle plates 20, beyond the lowermost 75 extremities of the plates 16 and disposed therebeneath, project inwardly and downwardly toward the bottom of the journal box.

It not infrequently happens that hot boxes in the journals of railway rolling stock are caused by the collecting of waste and other absorbent packings, employed in the journal box, finding their way around, and upon the journals against and between said journals and the brass therefor. It is my intention to overcome this difficulty by the employment of the plates 16 upon the brasses having the bristles 19 arranged and shaped as best shown in Figure 2 of the drawing whereby the waste saturated with oils or other lubricants could not adhere to and follow around with the journals for final disposition between the journals and the brasses therefor.

By reason of the fact that the brush portions formed by the bristles 19 are concaved, a very close fit between the extremities of the bristles and the outer surface of the journal may be facilitated whereby the smallest portions or lintels of the waste will be retarded.

The baffle plates 20, incident to their particular shapes and dispositions with respect to the plates 16, will prevent pressure of the waste against the plates 16 but the flanges 22 will hold a quantity of the saturated waste in position for engagement with the journal whereby the latter will be lubricated incident to rotary contact therewith.

As a further requisite for the proper lubrication of the journal and prevention of waste and other packings collecting between the journal and brass therefor, I have employed adjusting elements for the plates 16, in the nature of shafts 23. Such shafts are carried by and outwardly projected from the outer sides of the plates 16 and extended through openings in the adjacent portions of the baffle plates 20. Adjusting means or nuts 24, carried upon the outermost projecting portions of the shafts 23 and abutting the outer surfaces of the baffle plates 20, provide the means of clearance regulation between the free ends of the bristles and the adjacent side of the journal. By reason of the fact that the flanges 22 will move in conjunction with the baffle plate 20, the saturated packing or waste supported thereby may be forced against the lower exposed portion of the journal in order that additional lubricant may be applied thereto.

Rolling stock equipped with this type of lubricator and replenished at regular intervals with suitable quantities of lubricant would keep the journals in working order and hot boxes would never occur incident to the collecting of waste and other packings between the journal and the brass therefor.

The invention is susceptible of various changes in its form, proportions and minor details of construction, and the right is here reserved to make such changes as properly fall within the scope of the appended claims.

Having thus described the invention, what is claimed is:—

1. A journal lubricator for use within the journal boxes of rolling stock comprising plate members, said plates being arranged upon and depending from the brass for the journal, bristles carried by and obliquely disposed from the inner sides of the plates adjacent the journal being shaped in conformity with the outer wall contour of the journal, baffle plates carried upon the attaching portions of the plate members, flanges arranged upon the ends of the baffle plates beyond the extremities of the plate members to retain a suitable quantity of the saturated waste within the journal box against the exposed portion of the journal between the bristle portions of the plate members, and adjusting elements carried by the plate members engageable with the baffle plates to regulate the clearance between the free extremities of the

bristles and the outer side wall of the journal.

2. A journal lubricator for use within the journal boxes of rolling stock comprising plate members, said plates being arranged upon and depending from the brass for the journal, bristles carried by and obliquely disposed from the inner sides of the plates adjacent the journal being shaped in conformity with the outer wall contour of the journal, baffle plates carried upon the attaching portions of the plate members being progressively outwardly flared therefrom and disposed throughout the major portions of their lengths in spaced relation to the plate members, flanges arranged upon the opposite ends of the baffle plates beyond the extremities of the plate members and projecting inwardly therebeneath to retain a suitable quantity of the saturated waste within the journal box against the exposed portion of the journal between the bristle portions of the plate members, and adjusting elements carried by the plate members engageable with the baffle plates to regulate the clearance between the free extremities of the bristles and the outer side wall of the journal to the extent of the space defined between the baffle plates and plate members.

In testimony whereof I affix my signature.

GEORGE CARR.
